UNITED STATES PATENT OFFICE

THEODORE WILLARD CASE, OF AUBURN, NEW YORK, ASSIGNOR TO CASE RESEARCH LABORATORY INC., OF AUBURN, NEW YORK, A CORPORATION OF NEW YORK

APPARATUS FOR PRODUCING PHOTOGRAPHIC RECORDS

Application filed March 4, 1927. Serial No. 172,911.

This invention relates to certain new and useful improvements in apparatus for producing a photographic record of light wave variations corresponding to sound wave variations.

The invention resides more specifically in the construction, form, size and operation of the light source which is varied by variations in an electrical current corresponding to sound waves.

One of the objects of the invention is the production of a light source of high intensity, the electrodes of which are in such a position that sputtering cannot dirty the wall of that portion of the bulb through which the light is photographed.

A further object resides in the provision of a very small bulb including a small diameter comparatively short capillary whereby the desired light intensity is produced and the rays are brought to the slit past which the film moves along lines substantially perpendicular to the film.

A further object resides in the provision of a light source including a bulb and suitable electrodes therein, in which the bulb includes a small capillary adapted to be photographed from the side rather than from the end.

Other objects and advantages relate to the details of the structure and the form and relation of the parts thereof, all as will more fully appear from the following description taken in connection with the accompanying drawings, in which:

The figure is a diagrammatic illustration of an embodiment of the invention.

The apparatus as illustrated comprises a bulb —1— of glass or other suitable material and comprising two chambers —2— and —3— lined substantially side by side and connected together at one end of each chamber by a transversely extending small diameter short capillary or tube —4—. This bulb —1— is adapted to be supported in front of a slit —5— in a wall —7— past which a film —6— is adapted to move in such a position that the moving film is subjected to the light rays emanating from the side of the capillary or tube —4—.

The slit —5— may vary somewhat in length, but a slit of .1 of an inch in length is satisfactory for my purpose. The bulb —1— contains an ionizable gas, preferably helium under desired pressure. An electrode —7— in the form of a filament is positioned in the chamber —3— and is adapted to be heated in any suitable manner, as by a circuit containing a source of potential —8—. The other chamber —2— contains an unheated electrode —9— connected in circuit with the electrode or cathode —7—, said circuit containing a source of potential —10— and preferably a resistance —11—, and where amplification is desired, the secondary —12— of a transformer, the primary —13— of which may be connected through any number of stages of amplification with a means for varying current flowing in the circuits, as for instance the microphone —14—, the microphone circuit including a source of potential with battery —15—.

The electrodes enclosed in the respective chambers are in such a position that sputtering will not darken the portion of the capillary —4— used for photographic purposes, and the electrodes as shown may partially underlie the inner wall of the respective chambers and to any extent desired.

The electrode —7— constituting the cathode, has a coating comprising an alkaline earth metal, preferably barium oxide, whereby electron emission can be obtained without much light from the electrode.

As stated, the photographic film moves past the side of the capillary —4— rather than the end of the same which permits the capillary to be supported very close to the slit —5—.

The entire bulb —1— should be very small, such for instance, that it can be enclosed in a tube an inch and a quarter in diameter. The length of the capillary —4— should not exceed one-half an inch, and preferably is not longer than one-fifth of an inch, and the nearer the length of the capillary approaches the length of the slit, the more nearly perpendicular to the film will be the rays of light emanating from the capillary.

The diameter of the capillary is preferably

about $\frac{1}{32}$ nd of an inch, but it may be somewhat larger, not to exceed one quarter of an inch, whereby the rays of light pass through the slit —5— to the film —6— in a direction substantially perpendicular to the film.

5 Altho the cathode —7— is here illustrated as a heatable electrode, a cold electrode may be used in its place, the main distinction being that by the use of a heatable cathode considerably less voltage is required for operating the device and low voltage telephonic currents are more readily and easily modulated.

10 The resistance of the small diameter capillary or tube —4— is so great as to result in an extremely intense concentrated glow in the capillary.

15 The figure of the drawings is of a diagrammatic nature and the film —7— is indicated as moving lengthwise of the capillary, whereas in operation it would preferably move crosswise of the capillary at substantially right angles to the direction indicated in the drawings.

20 Altho I have shown and described specific structures together with particular form and relation of the parts, I do not desire to restrict myself to the details of form or relation of the parts except where the same are specifically included in the claims hereto appended.

25 I claim:

1. A lamp for producing a photographic record of light wave variations corresponding to sound wave variations comprising a bulb formed in two chambers which lie side by side, and a capillary connecting the two chambers on a line lying outside the limits thereof, an electrode in each chamber, and a circuit connecting the electrodes.

30 2. A lamp for producing a photographic record of light wave variations corresponding to sound wave variations comprising a bulb formed in two chambers and a tube of a diameter not greater than one-eighth of an inch extending transversely of and connecting the two chambers on a line lying outside the limits of the chambers.

35 3. A lamp for producing a photographic record of light wave variations corresponding to sound wave variations comprising a bulb formed in two chambers lying side by side, a tube having a diameter not substantially greater than one-eighth of an inch extending transversely of and connecting said chambers on a line lying outside the limits of the chambers, an electrode in each of said chambers and so positioned that sputtering will not dirty the effective portion of the wall of said tube, and a circuit connecting 40 said electrodes.

4. A lamp for producing a photographic record of light wave variations corresponding to sound wave variations comprising a bulb formed in two chambers and a tube 45 connecting the chambers on a line lying out-

side the limits of the chambers, said tube being of a diameter not substantially greater than $1/32$ nd of an inch, an electrode in each chamber and a circuit connecting the electrodes.

50 5. A lamp for producing a photographic record of light wave variations corresponding to sound wave variations comprising a bulb formed in two chambers and a tube connecting the chambers on a line lying outside the limits of the chambers, said tube being of a diameter not substantially greater than $1/32$ nd of an inch, an electrode in each chamber, a circuit connecting the electrodes, and means for heating one of the electrodes.

55 6. A lamp for producing a photographic record of light wave variations corresponding to sound wave variations comprising a bulb formed in two chambers which lie side by side and a capillary extending transversely of and connecting the two chambers on a line lying outside the limits of the chambers, an electrode in each chamber, the cathode of said electrodes comprising an alkaline earth metal, and a circuit connecting the electrodes.

60 In witness whereof I have hereunto set my hand this 22nd day of February, 1927.

THEODORE WILLARD CASE.
